United States Patent Office.

JOSHUA B. BARNES, OF FORT WAYNE, INDIANA.

Letters Patent No. 65,465, dated June 4, 1867.

IMPROVEMENT IN PIPE AND STUD-WRENCHES.

The Schedule referred to in these Letters Patent and making part of the same.

TO ALL WHOM IT MAY CONCERN:

Be it known that I, JOSHUA B. BARNES, of Fort Wayne, and State of Indiana, have invented certain new and useful improvements in Pipe and Stud-Wrenches; and I hereby declare that the following is a true, full, and exact description of the same, reference being had to the accompanying drawings, and to the letters of reference marked thereon.

The nature of my invention consists in providing the back part of the upper end of the handle with a rack, and also in the combination therewith of the several devices herein set forth. In the drawings annexed, which make a part of this specification—

Figure 1 represents a plan view of my wrench.

Figure 2 is a side view of the same.

Figure 3 gives a central longitudinal section of the wrench.

The handle *a* is formed with a plane surface on its upper and lower sides, and widens by an outward curve at its operating end. (See fig. 1.) The end thus widened is serrated at top, and constitutes the jaw *n* of the wrench. *e* represents the head, or, more properly, the upper jaw of the wrench. The jaw *e* is furnished with two shanks, which embrace the wrench and play on a pivot passing through said wrench; said jaw widens at top and is curved in the manner represented by fig. 1. On the under side of the curved end of the jaw *e* a nearly rectangular depression is made, and serrated in a manner similar to the lower jaw already described. It will be remarked that when a cylindrical rod is placed between these serrated jaws, and the upper jaw *e* shall be operated in the manner hereinafter described, that the said rod will be held as long as desired in an immovable position. *d* represents a pawl, one end of which is riveted to the metal plate *g*, the plate *g* being pivoted in an opening made to receive it on the outer side of jaw *e*. The end of plate *g*, to which the pawl is riveted, is acted on by the spiral spring *c*, shown in fig. 3. It will be seen that the spring *c* will, by its operation, force up the end of the plate on which the pawl rests, and the other end of the pawl will be driven between the teeth of the lower jaw of the wrench, and there held at the pleasure of the operator.

In the use of my wrench the following rule will be observed: With the right hand disengage the pawl from the teeth in the wrench, and with the left hand push back the jaw *e* as far as required. Let the wrench now embrace the rod or other object to be held, and move forward the jaw *e* as far as needed, and the pawl *d* will hold it firmly in its position.

Having thus described my invention, what I claim, and desire to secure by Letters Patent, is—

1. The handle *a*, when the back portion of the upper end shall be provided with a rack, in combination with jaw *e*, as and for the purpose specified.
2. The pawl *d*, spring *c*, and jaw *e*, all combined and operated as and for the purpose described.

In testimony whereof I set my signature in presence of two witnesses.

JOSHUA B. BARNES.
